(57) **CLAIM**
The ornamental design for a vehicle dock for portable computer, as shown and described.

(**) Term: **14 Years**

DESCRIPTION

(21) Appl. No.: **29/497,448**

FIG. 1 is a front perspective view showing a first embodiment of my new design;
FIG. 2 is a bottom perspective view of the first embodiment of my new design;

(22) Filed: **Jul. 24, 2014**

FIG. 3 is a front view of the first embodiment of my new design;
FIG. 4 is a rear view of the first embodiment of my new design;

(51) LOC (10) Cl. **08-07**

FIG. 5 is a left side view of the first embodiment of my new design;
FIG. 6 is a right side view of the first embodiment of my new design;

(52) U.S. Cl.

FIG. 7 is a top view of the first embodiment of my new design;
FIG. 8 is a bottom view of the first embodiment of my new design;

USPC **D14/447**

FIG. 9 is a reference perspective view showing the usage state of vehicle dock for portable computer;
FIG. 10 is a front perspective view showing a second embodiment of my new design;

(58) **Field of Classification Search**

FIG. 11 is a bottom perspective view of the second embodiment of my new design;
FIG. 12 is a front view of the second embodiment of my new design;
